UNITED STATES PATENT OFFICE.

WILHELM TETZLOFF, OF NEW RICHLAND, MINNESOTA.

ROAD GRADING AND DITCHING PLOW.

1,212,421.

Specification of Letters Patent. Patented Jan. 16, 1917.

Application filed October 6, 1915. Serial No. 54,465.

To all whom it may concern:

Be it known that I, WILHELM TETZLOFF, a citizen of the United States, residing at New Richland, in the county of Waseca, 5 State of Minnesota, have invented certain new and useful Improvements in Road Grading and Ditching Plows; and I do hereby declare the following to be a full, clear, and exact description of the invention, such as will enable others skilled in the art to which it appertains to make and use the same.

The present invention is directed to improvements in road grading and ditching 15 plows, and has for its object to provide a device of this character constructed in such a manner that the same can be adjusted for digging ditches of different depth.

A further object of the invention is to 20 provide a plow of this nature constructed in such a manner as to be used for maintaining roadways in proper condition.

With these and other objects in view, this 25 invention resides in the novel features of construction, formation, combination and arrangement of parts to be hereinafter more fully described, claimed and illustrated in the accompanying drawing, in which:—

Figure 1 is a side elevation of the plow. 30 Fig. 2 is a bottom plan view. Fig. 3 is a transverse section taken through the forward end of the plow.

Referring to the drawing 1 indicates an 35 arched frame, which supports the shaft 2, said shaft being provided centrally with a bearing 4 in which is rotatably journaled the lower end of the threaded shaft 5, said shaft being also journaled in the bight of the frame 1, and has its upper end provided 40 with a four-armed lever 6, which serves to rotate the shaft 5.

The forward end of the plow beam 7 has 45 secured thereto spaced plates 8, both of which are provided with slots 9, and extending longitudinally of the slots are fingers 10, which are adapted to engage the nut 11, said nut being threaded upon the shaft 5 and held against rotation by the fingers 10. Thus it will be seen that upon rotation of 50 the shaft 5 that the plow beam 7 can be raised or lowered to change the pitch of the heel 12, landside 13, and the mold board 14, which has its lower edge connected to the

heel 12 and its forward edge to the rear end of the beam 7. A slide bar 15 is provided, and has its forward end connected to the forward end of the heel 12, while the rear end thereof is curved upwardly and connected adjacent the rear end of said heel. A brace bar 16 is provided and has one of 55 its ends connected adjacent the rear end of the landside 13, said bar being passed through a slot 17 formed in the slide bar 15. The other end of the bar 16 is secured adjacent the rear end of the heel 12. The 60 plow is further braced by a bar 18, which has its upper end fixed adjacent the rear end of the mold board 14, and its lower end fixed 65 adjacent the end of the landside 13.

Fixed to the rear end of the mold board 70 14 is a curved plate 19, to the outer end of which is attached the rear end of a rod 20, the forward end of which is attached to the shaft 5, said rod serving to effectually brace 75 the plate 19, which serves to level the earth removed by the plow.

Pivottally associated with the shaft 5 is a clevis 21, to which may be attached the team of horses, for light work, or for attaching a tractor when the device is used 80 for heavy work.

From the foregoing description it will be seen that a plow has been provided so constructed that the same can be adjusted for plowing at different depth, upon simply rotating the shaft 5.

The sides of the frame 1 have suitably 85 attached thereto vertically spaced bearings 22 which rotatably receive the spindles of the caster wheels 23, said wheels serving to 90 support the forward end of the device. Having their rear ends fixed to the spindles are arms 24, the outer ends of which are pivotally connected to the adjacent ends of links 25, the other ends of which are pivotally 95 connected to the clips 26 carried by the sides of the clevis 21. Thus it will be seen that when strain is applied to the clevis, which is pivoted to the beam, the spindles will be rotated thereby allowing the wheels 100 23 to efficiently guide the device.

What is claimed is:—

A plow of the class described, in combination with an arched frame, a threaded shaft associated with the frame, an axle 105 carried by the frame, wheels mounted on

the axle, a bearing carried by the axle and rotatably engaged by the lower end of the shaft, plates carried by the plow beam, said plates having fingers carried thereby, a nut engaged on the shaft and held against rotary movement by said fingers, as and for the purpose set forth.

In testimony whereof, I affix my signature, in the presence of two witnesses.

WILHELM TETZLOFF.
